UNITED STATES PATENT OFFICE.

GEORGE FAILING, OF PHILADELPHIA, PENNSYLVANIA.

BOTTLE-CAPPING MACHINE.

1,143,819.

Specification of Letters Patent. Patented June 22, 1915.

Application filed January 25, 1912, Serial No. 673,286. Renewed December 14, 1914. Serial No. 877,221.

To all whom it may concern:

Be it known that I, GEORGE FAILING, of Philadelphia, in the county of Philadelphia and State of Pennsylvania, have invented 5 certain new and useful Improvements in Bottle-Capping Machines, whereof the following is a specification, reference being had to the accompanying drawings.

The invention relates more particularly 10 to a feeding mechanism for a bottle capping machine.

An object of the invention is to provide a feeding mechanism whereby the bottles may be placed underneath the capping head, 15 which feeding mechanism is so timed as to place the bottles or remove the same from capping position while the head is raised.

A further object of the invention is to provide a device of the above character, 20 which is so constructed that the feeding mechanism may be adjusted and adapted for various size bottles.

These and other objects will in part be 25 obvious, and will in part be hereinafter more fully described.

In the drawings which show by way of illustration one embodiment of the invention, Figure I, is a side elevation with parts in section, showing a machine embodying 30 my improvements. Fig. II, is a side view showing the supporting table, feeding device, and the operating mechanism therefor; Fig. III, is a plan view of the same. Fig. IV, is a section on the line IV, IV, of 35 Fig. I. Fig. V, is a detail showing in plan, a portion of the feed wheel and the reducing segment which adapts the feed wheel for smaller size bottles. Fig. VI, is a sectional view on the line VI, VI, of Fig. V. 40 Fig. VII, is a detail showing a section through the supporting table, and the yielding support for the bottles.

The bottle capping machine herein illustrated, consists of a supporting base 1, from 45 which rises a standard 2. Reciprocating in the standard 2, is a rod 3, on which is mounted the bottle capping head 4. The bottle capping head 4, is provided with a slide 5, which engages between spaced 50 brackets 6, which guide the head as it reciprocates, and prevents lateral movement thereof. The caps are automatically fed to the head through a chute 7. The rod supporting the head is reciprocated from the 55 main shaft 8, by a crank 9, which is con-

nected by the link 10, to the lower end of the rod. This shaft is driven through a loose pulley 11, which is connected to the shaft by a suitable clutch 12. The clutch 12, is spring-pressed toward the pulley, and engages a slot in the pulley. This clutch is released from the pulley by a slide 13, having a tapered end, and the slide is normally spring-pressed upward so as to release the pulley. 60

A foot lever 14, is formed with a latch 15, at its inner end, and by depressing the treadle, the slide 13, is released, thereby withdrawing the clutch bolt from engagement with the pulley and rendering the machine idle. Extending laterally from the standard 2, is a lug or arm 16, which is provided with an opening adapted to freely receive a casing 17. This casing is provided at its upper end with a support for the 70 bottle, and said support rests on a spring in the casing. On the outer face of the support, is an elastic pad (see Fig. VII). The purpose of this yielding support is to allow the bottle to yield during the capping action, to accommodate any slight inequalities in bottles of the same general size or capacity. This casing is mounted on a screw 75 18, at its lower end, and by adjusting the screw, the height of the casing may be varied so as to accommodate bottles of different general sizes or capacities. The bottle is placed on the yielding support, and the cap is fed underneath the capping head 80 and as the head descends, the cap will be placed on the bottle and properly fastened thereto. 90

The parts above described, are of the usual construction in crown seal bottle capping machines, and a further detailed description thereof is not thought necessary. 95

The principal object of the present invention is to provide means for feeding the bottles one at a time beneath the capping head, and the placing of the same on the pad carried by the yielding support, so that the bottle may be properly capped, and subsequently removing the bottle after it is capped. To this end, I have provided a projecting bracket 19, on which is mounted a 10 supporting table 20. This table is formed with a guiding flange 21, and a second guiding flange 22. The table is preferably so constructed as to have a radial extension, leading toward the center of the supporting 11

post of the capping machine, a concentric portion along which the bottles may be slid around the post to capping position, and away from capping position, and a final extension by which the bottles are conveyed from the machine.

In order to move the filled bottles over the table, I have provided a conveyer 23, which is mounted to turn about the axis of the supporting post. Said conveyer is formed with a plurality of segmental pockets 24, which are adapted to receive the bottles and to move the same along the supporting table. This conveyer is attached to a gear 25, turning also concentrically about the post, and said gear is driven by a second gear 26, which is mounted on the upper end of a vertical shaft 27. The vertical shaft 27, at its lower end, engages a bevel gear 28, which operates with a bevel gear 29, on the horizontal shaft 30. The horizontal shaft 30, carries the radius wheel 31, of a geneva stop motion. Said stop motion includes a disk 32, which carries the clutch 12, and this disk is keyed to the shaft 8. The disk 32, is cut away as shown in dotted lines at 33, in Fig. II. Said disk is also provided with a pin 34, which is adapted to enter radial grooves 35, of wheel 31. Through this mechanism, the carrier is given an intermittent motion, which will slide the bottles along the table to capping position where said carrier is caused to dwell while the cap is being placed on the bottle. After the bottle is capped, the carrier is again rotated to convey the bottle from beneath the head, and to place another bottle underneath the same. This carrier is of course, timed so as to place the bottles beneath the capping head when said head is raised. Said table is cut away as at 36, directly over the pad of the yielding support for the bottle, so that when the bottle is directly over the support, it will rest on the support, and not on the table, and therefore, said bottle may yield during the capping action. The bottles are withdrawn from the conveyer by a stripping finger 37, which forms a part of the guiding ledge 21, and overlaps the carrier on the delivery side thereof.

In order that the table may be adjusted to accommodate bottles of different sizes, the bracket 19 is held on the standard by a set screw 38. By releasing this set screw 38, the supporting table and the conveyer may be raised and lowered so as to be properly positioned for supporting and conveying the bottles beneath the head and on to the yielding support therefor. In order to allow of this adjustment of the conveyer, the vertical shaft 27, is formed in sections, as clearly shown in dotted lines in Fig. I. The upper section, together with the gear wheel 26, is supported by an arm 39, which is carried by the bracket 19. The upper section of this

vertical shaft has a sleeve 40, clamped thereon. This sleeve 40, telescopes the lower section of the shaft, and a key 41, will cause the rotation of one section of the shaft to be imparted to the other section, and allow the table to be raised simply by the releasing of the set screw 38, and the raising of the bracket 19.

In order to adjust the size of the segmental pockets in the conveyer for smaller sections, I have provided a removable segment 42. The conveyer is provided with an upwardly projecting lip around the pockets, and this segment rests on this lip and partially fills the pocket so as to reduce the size thereof.

It is obvious that minor changes in the details of construction and arrangement of parts, may be made without departing from the spirit of the invention as set forth in the appended claims.

I claim:-

1. A bottle capping machine including in combination a standard, a bottle capping head mounted on said standard, an operating shaft, means for reciprocating said head from said shaft, a bracket adjustably carried by said standard, a supporting table mounted on said bracket, a conveyer carried by the bracket and mounted to turn about the standard as an axis and located above said table, a yielding support on which the bottles rest for capping, a bearing carried by said bracket, a shaft mounted in said bearing, and having operating connection with said conveyer at its upper end, said shaft having an operating connection with the shaft which reciprocates the head, whereby said conveyer is moved in timed relation to the reciprocations of said head.

2. A bottle capping machine including in combination a standard, bottle capping means carried by said standard, a vertically adjustable bottle support disposed beneath said means, a vertically adjustable conveyer mounted on said standard and rotatable about the axis of said standard for moving said bottles onto said support, an operating shaft disposed below said conveyer, and means for rotating said conveyer from said operating shaft including an extensible driving shaft.

3. A bottle-capping machine including in combination, a standard, a bottle-capping head mounted on said standard, a shaft, means for reciprocating said head from said shaft, a bracket adjustably carried by said standard, a supporting table mounted on said bracket, a conveyer mounted to turn about the standard as an axis and located above said table, a yielding support on which the bottles are moved by the conveyer for capping, means carried by the table and co-operating with the conveyer for guiding the bottles to and from said yielding support,

and means for operating said conveyer from said shaft, whereby said conveyer is moved in timed relation to the reciprocation of the head.

4. In a bottle capping machine, a rotary bottle conveyer comprising a circular disk having peripheral bottle receiving pockets formed therein, said disk being formed with flanges respectively projecting upwardly from the walls of said pockets and remov-

able segments engaged with said flanges to vary the sizes of said pockets.

In testimony whereof, I have hereunto signed my name at Philadelphia, Pennsylvania, this twenty-third day of January 1912.

GEORGE FAILING.
